UNITED STATES PATENT OFFICE

95,482

DESIGN FOR A TABLE CENTERPIECE

Norman Bel Geddes, New York, N. Y., assignor
to Revere Copper and Brass Incorporated,
Rome, N. Y., a corporation of Maryland

Application February 13, 1935, Serial No. 55,392

Term of patent 7 years

To all whom it may concern:

Be it known that I, Norman Bel Geddes, a citizen of the United States, and a resident of the city, county, and State of New York, have invented a new, original, and ornamental Design for Table Centerpieces, of which the following is a specification, reference being had to the accompanying drawing, forming part thereof.

The drawing is a perspective of a table centerpiece, showing my new design. The recesses at each end of the article are candle holders.

I claim:

The ornamental design for a table centerpiece, substantially as shown and described.

NORMAN BEL GEDDES.
